UNITED STATES PATENT OFFICE.

GARRET B. OSTERHOUT, OF PROVIDENCE, RHODE ISLAND, ASSIGNOR TO WILLCOX & GIBBS SEWING MACHINE CO., OF NEW YORK, N. Y., A CORPORATION OF NEW YORK.

LOOPER AND LOOPER MECHANISM.

1,253,519.

Specification of Letters Patent. Patented Jan. 15, 1918.

Application filed April 5, 1917. Serial No. 159,983.

To all whom it may concern:

Be it known that I, GARRET B. OSTERHOUT, a citizen of the United States of America, and a resident of Providence, Rhode Island, have invented a new and useful Improvement in Loopers and Looper Mechanism, which invention is fully set forth in the following specification.

The present invention relates to improvements in loopers and looper mechanism for sewing machines, designed especially for use with what is known commercially as the Wilcox & Gibbs Sewing Machine Company's "Flatlock machine," shown, for example, in the patents to Stockton Borton No. 1,041,574 and A. A. Merritt No. 1,041,652, both dated October 15, 1912, and producing the seam of Patent No. 883,614, dated March 31, 1908, to said Stockton Borton. This invention is not, however, restricted to use with any particular type or make of sewing machine.

With the thread eye of each looper extending transversely through the body of the looper, that is, with the longitudinal axis of the eye approximately perpendicular to the longitudinal axis of the looper, as shown in the patents aforesaid, the looper thread, extending along one side of the looper to the eye thereof, tends to bow out or stand away from the looper, beginning at the looper eye, in a position to be stabbed or impaled by one of the descending needles. This results in breaking the looper-thread, necessitating stopping and rethreading of the machine, or otherwise interferes with the proper stitch formation. Experience shows this most likely to happen when a soft yarn is used as the looper thread.

Briefly stated, the present invention consists in forming the thread-eye through the body of the looper in a diagonal direction. In other words, the eye is so formed through the looper that the longitudinal axis of the eye is slanted or inclined to the longitudinal axis of the looper, the exit end of the eye being nearer the point of the looper than the entrance end of said eye. This results in holding the looper thread in proper position and out of the path of the point of the

needle as the same descends close to the looper and enters a loop of looper-thread from a neighboring looper. The structural embodiment of the invention and the functioning thereof in accomplishing the stated result may be more readily explained and understood by reference to the accompanying drawing illustrating what is now believed to be the preferred embodiment as applied to a machine of the character of the aforesaid "Flatlock machine." In said drawing—

Figure 1 is a vertical sectional view showing stitch-forming elements of the machine in their relative positions when the points of the needles have passed through the throat-plate and are just entering the spread loops in the looper-threads;

Fig. 2 is a view looking down on the elements below the throat-plate (also showing the lower ends of the needles in section) when the parts are in the position shown in Fig. 1. The loops of needle threads around the loopers, shown in Fig. 1, have been omitted in Fig. 2.

Fig. 3 is a face view of one of the loopers; and

Fig. 4 is a longitudinal sectional view through the looper of Fig. 3.

1, 2, 3 and 4 are a gang of four parallel needles each carrying a needle thread. They are secured to a common needle bar and reciprocate together. In addition to the four needles, the hook 101 having a depending horn 5^c, and a thread carrier (not shown), work above the throat-plate, these parts co-operating with the needles to incorporate in the upper face of the seam, in its proper position, a cross-thread 5. A part of the presser-foot is shown at 26, and a part of an auxiliary foot, yieldingly carried by the main presser-foot and designated a "chaining" foot, is shown at 25. 28 is the throat-plate and 30 a piece of fabric on which the mechanism is operating.

Below the throat-plate, there is a feed-surface, portions of which are shown at 20 and 22, operating upwardly through openings in the throat-plate to advance the work, the movement of the feed-surface be-

ing approximated by the ellipse 166 in dotted lines, Fig. 1. 14 is an oscillatory loop-spreader having three thread-engaging hook points or teeth—see Osterhout Patent No. 1,134,483 of April 6, 1915. 15 is a loop-shedder fixed rigidly to the underside of the throat-plate 28 and acting to prevent movement of the loops in the needle-threads as the loopers are withdrawn from said loops.

10 6^a, 7^a, 8^a and 9^a are four loopers, each having a depending right-angled shank, shown in Fig. 3, through which screws, only one of which is shown at 193, pass to bind the four loopers together and secure them to the 15 looper carrier, a part only of which is shown at 183. The screws mentioned also secure a plate 191 to the looper carrier. In coöperation with the other parts of the mechanism, the loopers are moved in an 20 elliptical path in a substantially horizontal plane, such elliptical movement being approximated by the dotted line ellipse 199, Fig. 2, for the point of looper 6^a. The third looper 8^a is notched on its upper edge to 25 form a tooth or hook 10, adapted to engage and position looper thread 7, as and for the purpose more fully set forth in the Patent No. 1,041,698, dated October 15, 1912, to A. B. Tabor.

30 As thus far described, the construction is substantially the same as disclosed in the Tabor and other patents aforesaid.

Each looper, for example, looper 9^a shown in Figs. 3 and 4, has a thread groove extending from its rear end to the thread-eye α near the point of the looper. Said eye, instead of passing at right-angles through the body of the looper as is customary, is on a diagonal or slant, that is to say, the axis of 35 the eye is inclined to the longitudinal axis of the looper, the end of the eye at which the thread makes its exit being nearer the point of the looper than the other end of the eye where the thread enters. The thread in passing through the eye α is only slightly deflected from a straight line path, is caused to lie closely against the side of the looper and in the groove thereof, obviating bowing or 40 spreading of the thread away from the looper into position to be stabbed or impaled by a needle descending close to the looper. Thus, for example, in the descent of the needle 2 across the side of looper 9^a and close thereto, the looper-thread 9 is out 45 of the way and there is no danger of the point of the needle stabbing, impaling or breaking said thread. The inclination of the eye α of each looper also tends to position the exit end of said eye forward of the line 50 of the needles, which line is transverse to the length of the loopers; and to position the entrance end of the eye rearward of said line—when the parts are in the position shown in Figs. 1 and 2, with the points of 55 the needles passing the loopers. See, for

example, the eye of looper 9^a in Fig. 2, with needle 3 descending close to one side of said looper to the rear of looper-thread 9, and the needle 2 descending close to the other side of said looper with no danger of impaling or stabbing its thread.

What is claimed is:—

1. In a sewing machine, the combination of a thread-carrying looper and driving connections therefor, said looper having a 75 thread-eye therethrough with its longitudinal axis diagonal to the longitudinal axis of the looper and the thread exit end of the eye nearer the looper point than the thread entrance end of the eye, and a 80 needle and driving connections actuating the same to cause the point thereof to move across and close to the looper near the thread entrance end of the looper eye and on the side of the looper at which said entrance end 85 of the eye is located.

2. In a sewing machine, the combination of a thread-carrying looper and driving connections therefor, said looper having a 90 thread-groove along one side thereof leading to a thread-eye, the longitudinal axis of said eye being diagonal to the longitudinal axis of the looper and the thread exit end of the eye nearer the looper point than the thread entrance end thereof, and a needle 95 and driving connections actuating the same to cause the point thereof to move across and close to the looper near the thread entrance end of the looper eye and on the side of the looper at which said thread entrance end 100 of the eye is located.

3. In a sewing machine, the combination of a thread-carrying looper and driving connections therefor, said looper having a 105 thread-eye therethrough with its longitudinal axis diagonal to the longitudinal axis of the looper and the thread exit end of the eye nearer the looper point than the thread entrance end of the eye and the looper thread being adapted to extend to the eye along a portion of the side of the looper in advance of the entrance end of said eye, and two 110 needles and driving connections actuating the same to cause the points thereof to move across the loopers on opposite sides thereof, the point of one of said needles moving close to the looper near the thread entrance end of the looper eye at the side of the looper at which said thread entrance end of the eye 115 is located.

4. In a sewing machine, the combination of a plurality of thread-carrying looper and driving connections for longitudinally moving them together, said loopers each having a thread-eye therethrough with its longitudinal axis diagonal to the longitudinal axis of the looper and the thread exit end of the eye nearer the looper point than the thread entrance end of the eye and the looper thread being adapted to extend to the eye along a 125

120

125

130

portion of the side of the looper which is in advance of the entrance end of said eye, a plurality of needles alined approximately at right-angles to the longitudinal axes of the loopers, and driving means actuating said needles together to cause the point of each needle to move across and close to its respec-

tive looper near the thread entrance end of the looper eye at the side of the looper at which said thread entrance end of the eye is 10 located.

In testimony whereof I have signed this specification.

GARRET B. OSTERHOUT.
